CLAIM

U.S. PATENT DOCUMENTS

The ornamental design for a speakerphone, as shown.

DESCRIPTION

D220,105 S 3/1971 Small
D257,346 S 10/1980 Garrigus et al.
D263,588 S 3/1982 Hillmer
4,378,468 A 3/1983 Braun
D292,283 S 10/1987 Matsuda et al.
D300,322 S 3/1989 Lam
D311,397 S 10/1990 Cheng
D315,562 S 3/1991 Brown
D326,452 S * 5/1992 Roegner D14/138
D327,479 S 6/1992 Britz
D342,732 S 12/1993 Hinman et al.
D355,416 S 2/1995 McCay et al.

FIG. 1 is a perspective view of a speakerphone showing our
new design;

FIG. 2 is a front view thereof;

FIG. 3 is a back view thereof;

FIG. 4 is a left-hand view thereof;

FIG. 5 is a right-hand view thereof; and,

FIG. 6 is a top view thereof.

The broken line showings throughout the views are for
illustrative purposes only and form no part of the claimed
design.
